CLAIM

The ornamental design for a catcher's mask visor, as
shown and described.

DESCRIPTION

FIG. 1 is a front elevational view of a catcher's mask visor showing my new design;

FIG. 2 is a top plan view thereof;

FIG. 3 is a bottom plan view thereof;

FIG. 4 is a rear elevational view thereof;

FIG. 5 is a right side elevational view thereof; and,

FIG. 6 is a left side elevational view thereof.

The mask shown in broken lines in FIGS. 1, 5 and 6 is
shown for illustrative purposes only and forms no part
of the claimed design.

FIG. 2

FIG. 1

FIG. 3

FIG. 4

FIG. 5

FIG. 6
